Application December 22, 1950, Serial No. 202,154

18 Claims. (Cl. 33—22)

1

Our invention relates to engraving machines, and more specifically to those types of machines for cutting or engraving designs, indicia and the like, on the circumferential, curved, exterior surfaces of cylinders, rolls or similar work pieces; and the objects and nature of the invention will be readily recognized and understood by those skilled in the art, in the light of the following explanation and detailed description of the accompanying drawings illustrating one possible embodiment or mechanical expression of our invention from among other forms, embodiments, expressions, designs, constructions and combinations, of which the invention is capable within the broad spirit and scope thereof.

One of the primary objects of our invention is to provide improvements in engraving machines for cutting or engraving designs, indicia and the like on, and either completely or partially around, the circumferential surfaces of cylinders and rolls of substantial weights, lengths and diameters, in accurate scaled reproduction of a master design or pattern.

A type of engraving machine utilizing a tracer controlled pantographic linkage for cutting or engraving designs on the circumferential surface of a cylinder or roll in scaled reproduction of a master design or pattern, is disclosed in the U. S. Patent 2,110,873 to George Gorton et al., dated March 15, 1938. The engraving machine disclosed in the aforesaid patent is on the market and in successful use but is capable of only handling and engraving upon cylinders or rolls within a limited range of weights, lengths and diameters, and is not adapted to engraving on rolls of substantially greater weights, lengths, and diameters. The machine organization of the above identified U. S. patent provides a rotary work holder, a stylus, a pantograph linkage, a tool spindle, and mechanisms associating such components, in a manner such that when operated in combination, the cross movements of the tracer or stylus relative to the machine in following a master design or pattern, effect movements of the pantograph linkage which in turn causes cross movement of both the roll or cylindrical work piece and the tool and synchronized rotation of the work piece. The tool is maintained at all times "centered" relative to the work piece, that is, with its axis perpendicular to and lying in the same plane as the longitudinal axis of the work piece. The tool which is "centered" is capable of cross movements under the control of the pantograph linkage and is synchronized with the movements of the work

piece. While the machine of the aforesaid patent is capable and efficient in operation within the work piece capacity of the machine, the sensitivity and precision in operation thereof are dependent upon the size and weight of the cylindrical work piece, that is, sensitivity and efficiency of operation are effective only in engraving upon work pieces within a limited range of work piece weights and dimensions. As the machine organization of said patent requires transportation and movements bodily of the work piece across the machine in performing the engraving operations, in addition to rotation of the work piece, guideways and the necessary associated structures are required for carrying out such transportation and movements bodily of the work piece. Hence, in order to adapt a machine of the patent organization to accommodate and handle and to engrave upon the surfaces of, rolls or cylinders of substantially greater weights, lengths and diameters, than those for which the organization is adapted, it would be necessary to provide a machine of massive and impractical proportions and dimensions with all of the supporting members proportionately increased in size, weight and strength, in order to support a roll or cylinder of such substantial weight and size for movements bodily, while retaining for the machine the essential sensitivity and precision in operation.

A machine of our present invention may be considered to constitute in certain respects, an improvement on the machine organization of the above identified U. S. patent, and it is, therefore, another object to eliminate certain of the disadvantages and work limitations of the machine of said patent, and to provide a machine capable of efficiently engraving upon the circumferential surfaces of cylindrical work pieces of substantially greater weights, diameters and lengths than can be practically and efficiently handled and engraved by the machine organization of the patent.

A further object is to provide a design of roll engraving machine of the tracer controlled, pantograph type in which the work piece or roll during engraving operations is maintained in a fixed position for rotation about a fixed axis to thereby eliminate the necessity for movements bodily of the work piece in either directions axially or laterally relative thereto.

Another object is to provide such a tracer controlled, pantograph engraving machine for engraving upon the circumferential surfaces of cylindrical, roll-like work pieces in which the

rectilinear movements of the tracer in and out relative to the machine and transversely of the work piece in following a master pattern are converted into rotary movements of the work piece in synchronization with and in scaled relation to the movements of the tracer.

Another object is to provide such a machine in which the movements of the tracer or stylus in following the pattern in directions cross-wise of the machine and axially or longitudinally relative to the cylindrical work piece being engraved, are translated as cross-wise movements of the cutter along and constrained to a straight line path parallel with the longitudinal axis of the work piece and with the cutter maintained at all times with its axis perpendicular to and in a plane passing through such work piece longitudinal axis.

Another object is to provide such a machine in which the cutter is constrained against movements in and out relative to the machine and transversely relative to the work piece, but is mounted for movements along and constrained to a straight line path parallel with the longitudinal axis of the work piece with the axis of the cutter maintained perpendicular to the axis of the work piece.

A further object is to provide mechanism in such a machine actuated by movements of the tracer controlled pantograph for rotating the work piece, in which slippage or lost motion and backlash are substantially eliminated to insure accuracy of reproduction.

A further object is to provide a novel tracer controlled pantograph mechanism for converting rectilinear movements of the tracer or stylus in one dimension into rotary movements in such dimension of a work piece or other element in precisely scaled relation to the tracer movements.

Another object is to eliminate the use of toothed driving and driven elements, such as gears, pinions, racks and the like, in a tracer controlled pantograph mechanism for transmitting and converting rectilinear movements of the tracer or stylus into rotary movements of a work piece or other driven member.

Another object is to provide for selective, precise adjustment of such a tracer controlled, pantograph mechanism to set the mechanism to effect by a given linear movement of the tracer, a degree of rotation of the work piece in accordance with the diameter of the work piece, so as to maintain accurately a predetermined ratio between the linear movements of the tracer and the rotary movement of the work piece for work pieces of different diameters.

And a further object is to provide a design of roll engraving machine carrying out the foregoing objects and features, which will be of practical dimensions and weights to occupy a minimum of floor space, while being capable of handling and engraving with a high degree of precision on and around the circumferential surfaces of cylindrical or roll-like work pieces of substantially great lengths, diameters and weights.

With the foregoing and various other objects, features and results in view, which others will be readily apparent to those skilled in this art, our invention consists in certain novel features in design and construction and in arrangements, combinations and sub-combinations of parts, components and mechanisms, all as will be more fully referred to and specified hereinafter.

Referring to the accompanying drawings in which similar reference characters refer to corresponding parts and elements throughout the several figures thereof.

5 Fig. 1 is a view in top plan of a roll engraving machine of our invention, showing a roll-like work piece in mounted position on the work table for reproduction thereon of a pattern mounted on a copy table.

10 Fig. 2 is a view in side elevation of the machine of Fig. 1.

20 Fig. 4 is a view in side elevation of the movement converting and ratio compensating mechanisms from the pantograph to the rotary work holder.

25 Fig. 5 is a view in front elevation of the mechanisms of Fig. 4.

30 Fig. 6 is a detail view in side elevation of the scale mounting bar member of the ratio compensating mechanism.

35 Fig. 7 is a more or less schematic view in elevation of the band carriage, bands and drum rotated thereby for converting rectilinear into rotary movements.

40 Fig. 8 is a more or less schematic view in side elevation of the arrangement of drums and bands of the movement transmitting mechanism for rotating the rotary work holder.

45 The particular roll engraving machine embodying our invention, as illustrated and described herein by way of example, is adapted to mount and to engrave upon the circumferential surfaces of, cylindrical, round or roll-like work pieces of diameters from six (6) inches, more or less, to twelve (12) inches, more or less, and of

lengths up to forty (40) inches more or less, with corresponding substantial weights depending upon the material of which the work piece is formed. The example machine and the range of work piece dimensions and weights as specified above, are not presented by way of limitation but merely to show the capacity of this particular machine to handle and accurately and with precision engrave upon the circumferential surfaces of cylindrical or roll-like work pieces of great

50 dimensions and weights. It will be recognized from the following explanation and description of this example machine, that other machines embodying the basic principles and features of our invention may be designed and constructed to handle and engrave upon work pieces of greater or lesser dimensions and weights than those for

55 which this particular example machine has been designed. It will also be recognized that the specific design of the example machine is not restrictive of our invention as to the general arrangement of the machine or as to specific designs, forms and constructions of the various

60 components and mechanisms making up the machine. The basic features of our invention by which a cylindrical or roll-like work piece is mounted and maintained for rotation in a fixed position against movements bodily during the engraving operations, and by which mechanisms

65 are provided for transmitting movements of a tracer or stylus over a pattern in scaled relation to a cutter in one dimension and for converting rectilinear movements of the tracer or stylus in the other dimension as solely rotation of the work

70 piece relative to the cutter, may be embodied and

75

75

combined in other designs and arrangements of machines than the design and arrangement generally typified by the example machine.

The example machine, referring now to Figs. 1 and 2 of the drawings in particular, comprises a horizontally disposed bed structure B with the generally vertically disposed column structure C in position thereon extended vertically upwardly from the rear end portion thereof. The upper side of bed structure B is generally horizontally disposed and mounts thereon the horizontal guideways 10 which extend longitudinally of the bed structure between column C and the forward end of the bed structure. A suitable saddle structure S is slidably mounted on guideways 10 for movements in either direction along a straight-line path in and out relative to column C and to the machine. A work table W is slidably mounted on and in position disposed transversely across saddle S in suitable guideways to permit of movements of the work table W on and relative to saddle S in either direction along a straight line path cross-wise relative to the machine and perpendicular to the path of in and out movements of saddle S.

A pattern or copy table D is mounted on a suitable supporting structure D', in position on and across the front or forward end of base structure B above and along the forward side of work table W. The copy table D is mounted and arranged to be easily moved from its normal operative position out and away from saddle S and work table W to permit of the free loading and unloading of the substantially heavy and large dimensioned work pieces which this machine is designed to mount and handle. This copy table D is provided on the upper side thereof with a horizontal, flat pattern or copy holder F on which copy in the form of a flat pattern or master P containing on the flat upper surface thereof the design to be reproduced, may be clamped in proper position on the upper surface of the copy table.

A rotary work holder or chuck unit H is mounted in normally fixed position at one end, in this instance the left hand end, of the work table W in position extended vertically upwardly therefrom for receiving and clamping therein one end of a cylindrical or roll-like work piece R. The work holder H is positioned for rotation about a horizontal axis and is adapted to mount one end of a work piece R therein with the work piece held in position horizontally disposed and extended inwardly therefrom longitudinally of work table W and cross-wise of the machine, for rotation about the horizontal axis of rotation of the work holder. The inner, free end of the roll or work piece R when mounted in work holder H may be supported on a suitable tail stock unit H' secured on work table W, as will be clear by reference to Fig. 1. Thus, a work piece R mounted in position in the work holder H on work table W is rotatable about a horizontal axis disposed cross-wise of the machine and parallel with the straight line path of cross-wise movements of table W on saddle S. The work piece R may be set in required position for an engraving operation by suitable adjustments of the saddle S to move the work piece in or out, and of the work table on and relative to the saddle, to move the work piece cross-wise, of the machine.

A cutter head 12 is supported in vertically disposed position above work table W and a work piece R mounted in work holder H on that table, by a system of jointed links 14 and 15. Link 14

is pivotally mounted at its rear end to a supporting bracket structure 24 attached to and extended forwardly from the forward side of column C, adjacent the upper end thereof. Link 14 extends forwardly from column C and supporting structure 24 and the link 15 is pivotally coupled at its inner or rear end to the forward end of link 14. The cutter head 12 is pivotally mounted on and coupled to the forward end of link 15. The cutter head 12 mounts and journals therein a vertically disposed cutter spindle 16 in the usual manner familiar in this art, with the lower end of spindle 16 providing the usual chuck or collet for removably mounting therein an engraving tool or cutter E. Thus, if unrestrained, as may be said to be conventional with this type of cutter head mounting, the cutter head 12 and spindle 16 would be capable of universal lateral movements over work table W and a work piece R mounted in the rotary work holder H.

However, in accordance with our present invention we constrain movements of the cutter head 12 to a straight line path cross-wise of the machine and parallel with the axis of rotation of the rotary work holder H and of the work piece R mounted therein, in a direction corresponding to one dimension of the pattern to be traced and reproduced. We have carried out this constraining of the cutterhead 12 against in and out movements relative to the machine in the instant example, by providing a pair of spaced, horizontally disposed slide rods 17 across the machine in position below but spaced at the rear of cutter head 12 and parallel with the axis of rotation of the work piece R when mounted in workholder H. These slide rods 17 are secured and fixed at their opposite ends in supporting arms 18 which are secured to opposite sides of the supporting structure 24 on which link 14 is pivotally mounted. These support arms 18 extend laterally outwardly from opposite sides of such structure and are curved or extended forwardly in generally parallel relation to receive therebetween the slide rods 17 with the opposite ends of these rods secured in the forward ends, respectively, of such support arms. A slide member 20 is slidably mounted on rods 17, and this slide member provides a forwardly, horizontally extended fixed link or arm 21 which may be formed with a vertically disposed circular bore forming an eye therethrough which receives therein the lower portion of cutter head 12, as will be clear by reference to Figs. 1 and 2. The mounting and position of the slide rods 17 which define the straight line path of cross-wise movements for and to which cutter head 12 is constrained, and of the cutter head and its spindle 16 relative to the work holder H and the work-piece R mounted therein, is such that the axis of the cutter spindle 16 is perpendicular to the common axis of rotation of work holder H and of workpiece R therein with these axes lying in a common vertical plane. In this manner the cutter spindle 16 is "centered" relative to a work piece and such centered position is at all time maintained by the slide member 20 confined on rods 17 against in and out movements, that is, movements transversely of a work piece R.

Any suitable or usual powered drive transmission, indicated generally by the reference characters 22, may be provided for rotating the cutter spindle 16 in the cutter head 12 in all positions of the cutter head.

A pantograph mechanism, indicated as a unit

by the reference character G, is mounted at the right hand side of cutter head 12 in horizontally disposed position over and above work table W and the slide rods 17 and their support arms 18. This pantograph mechanism G is of the parallelogram, jointed link type. The jointed links of the pantograph G are comprised by the pivotally connected arms 31, 32, 33 and 34.

Arm 31 is in this instance located at the outer side of the pantograph G with arm 32 pivotally connected at its outer end to the rear end of arm 31 by the pivot 36, and with the outer end of arm 34 pivotally connected to the forward end of arm 31 by pivot 35. The arm 31 is extended forwardly from pivot 35 to provide the tracer arm 30 extended over and across copy table D. Tracer arm 30 is provided at its forward, front and free end with a tracer and/or stylus holder 30a in which there is mounted in vertically disposed position a tracer T having the usual master or pattern scanning stylus at its lower end, as will be familiar to those skilled in this art. The arm 32 is pivotally connected at its rear, inner end to the rear end of arm 33 by a pivot 37. The forward end of arm 33 is extended to cutter head 12 and is provided with a suitable collar 39 which rotatably receives the cutter head 12 to thereby form a primary pivotal support point for the pantograph G. The inner end of arm 34 adjacent arm 33 is pivotally connected to arm 33 at a point spaced rearwardly therealong from the cutter head 12, by pivot 38 to thereby complete the parallelogram linkage of the pantograph unit G. The pantograph linkage G is thus mounted for lateral swinging about the axis of cutter head 12 and cutter spindle 16, in a plane generally perpendicular to that axis.

The inner end of the arm 32 is extended rearwardly and outwardly from the pivot 37, as an axial continuation of arm 32, to provide the arm 40 which constitutes the member or element by which in and out movements of the pantograph under the control of the tracer T in the in and out dimension, that is, transversely of a work piece, are transmitted to the mechanism for converting the movements of the end of arm 40 into rotary movements of the work holder H and a work piece R mounted therein.

A slide member 41 is slidably mounted on a pair of parallel, spaced and horizontally disposed slide rods 42 which are mounted and located on the cutter head support structure 24 carried by column C, in a location adjacent the left hand side of such structure. These slide rods are disposed in positions to extend in directions from front to rear (in and out) of the machine and transversely or perpendicular to the axes of the slide rods 17 for the cutter head slide member 20 and to the axis of rotation of the work holder H. The free end of the extended arm 40 of pantograph arm 32 is pivotally connected and coupled to slide member 41 by a pivot 43 which provides a pivotal axis perpendicular to the axes of the slide rods 42. The slide member 41 on slide rods 42 thus provides a floating pivot and pivotal support for the pantograph unit G between the end of extended arm 40 thereof and the slide member. Movements of the pivot 43 in scaled relation to in and out movements of the tracer T in following a pattern or master P on copy table D are thus transmitted to slide member 41 and translated thereby into straight line movements along the path defined by slide rods 42, in directions in and out relative to the machine and corresponding and in scaled

relation to the in and out movements of the tracer T.

Movements of the tracer T cross-wise of a pattern P and of the machine, that is, along straight line paths parallel with the axes of work piece rotation, will be transmitted through the pantograph G to the cutter head 12, and will effect only movements of the cutter head along its straight line path defined by the slide rods 17. Under such conditions of operation, no movements will be transmitted by the pantograph G through arm 40 thereof to the slide member 41 as arm 40 will merely float about pivot 43. However, in and out movements of tracer T over the pattern P along straight line paths perpendicular to the axis of work piece rotation, will be transmitted by the extended arm 40, through the floating pivot 43 to the slide member 41 to cause that member to move in corresponding directions along the straight line path defined by the slide rods 42. This is so because the cutter head 12 on which the pantograph unit G has pivotal support by slide member 20, is positively constrained by rods 17 against any in and out movements and such movements are thereby translated into movements of the slide member 41 by rotation or lateral swinging of the pantograph unit G in a horizontal plane about cutter head 12 as a fixed axis. With the arrangement and relative mounting of the pantograph unit G, pivotally supported on cutter head 12 for pivoting about the axis of that head and the cutter spindle 16, and pivotally coupled through extended arm 40 to slide 41 through pivot 43, it is to be noted that the axes of tracer T, cutter spindle 16 and floating pivot 43, are always maintained in a straight line, that is, always lie in a common vertical plane in all positions of operation of the pantograph unit.

We provide for rotating the work holder H to correspondingly revolve a work piece R clamped in working position therein, from the rectilinear movements of the slide member 41. We carry out the rotation of the work holder H through the medium of an organization or mechanism which converts the rectilinear movements of the slide member 41 into rotational movements of the work holder H, with such rotational movements of the work holder being synchronized with and in a definite predetermined ratio to the in and out movements of the tracer T over a pattern P in accordance with the diameter of a particular work piece being engraved. We also include in this movement converting organization, adjustable, ratio compensating means by which the degrees of rotational movements of a work piece may be adjusted in accordance with the diameter of that work piece, to thereby maintain a predetermined ratio of scaled reproduction between the in and out movements of the tracer T and the degrees of the resulting rotational movement of the work piece to move its circumferential surface relative to the cutter E.

In the particular mechanical expression of such movement converting organization of the example machine, we provide a slide carriage 50 which is mounted for reciprocation along a straight line path on and defined by a pair of parallel, vertically spaced, horizontally disposed slide rods 51 which are mounted in fixed position at the left-hand side of the machine below the slide member 41 to which the pantograph G is coupled by the floating pivot 43. The slide rods 51 are positioned with their axes parallel with the axes of slide rods 42 on which slide member

41 is mounted, that is, parallel with the straight line paths of in and out movements of tracer T and perpendicular to the straight line paths of cross-wise movements of the tracer.

This slide carriage 50 includes a body 52 which is provided at the forward, upper side thereof, with the horizontally disposed, laterally offset and generally parallel posts or arms 53. The posts or arms 53 are provided at their outer free ends with clamp plates 54, respectively, by which the ends of a pair of flat, flexible steel or the like, bands 55 and 56 are clamped to the ends of the arms 53.

At the outer side of and opposite the slide carriage 50, a shaft 57 is supported and journaled in a fixed bearing unit 57a. Shaft 57 is disposed in horizontal position with its axis in a plane passing below carriage arms 53 and perpendicular to slide rods 51 and to the straight line path of movements of the slide carriage 50 thereon. This shaft 57 mounts at its inner end for rotation therewith, an actuating drum 58 of a diameter such that a plane passing through the uppermost side of its periphery is in immediate proximity to the plane of the under surfaces of arms 53. The band 55 is attached to the rear end of the rearwardly extended arm 53 of carriage 50 by a clamp plate 54 and is extended forwardly across the upper side of the periphery of drum 58 and is then wound around the drum in a clockwise direction when facing the outer side of the drum, with the end of the band being fixed to the drum. The band 56 is attached to the forward end of the forwardly extended arm 53 of carriage 50 and is extended rearwardly to and across the upper side of the periphery of drum 53 and is then wound around the drum in the opposite direction from the direction of winding of band 55 on the drum, with the end of band 56 fixed to the drum. Band 56 is located on drum 58 to the rear of the band 55, due to the offset of the forward arm 53 inwardly relative to rear arm 53.

Hence, straight line movement of slide carriage 50 rearwardly on slide rods 51 will unwind band 55 from the drum 58 to rotate the drum counterclockwise when facing the drum from the left-hand side of the machine, and at the same time will wind band 56 onto the drum. Movement of the slide carriage 50 in the opposite direction, that is forwardly on slide rods 51, will reverse the action of the bands, in that band 56 will then unwind from drum 58 and effect rotation of the drum in a clockwise direction while the band 55 will be wound onto the drum. In this manner the rectilinear movements of slide carriage 50 forwardly or rearwardly in either direction along slide rods 51 will, through the arrangement of bands 55 and 56, convert such rectilinear movements into rotational movements of the drum 58 and shaft 57 in a clockwise or a counterclockwise direction, respectively. The length of the bands 55 and 56 and the mounting and attachment thereof on and to drum 58 and to the carriage arms 53, is such that the bands are taut, but without placing the bands under undue tension, so that no slack exists in the bands. Thus, a transmission which converts the rectilinear movements of carriage 50 into rotary movements of drum 58 is obtained which is free of slippage with backlash eliminated, so that a predetermined, fixed ratio between such movements may be maintained without material variation.

A transmission or drive is provided from shaft 57 to the rotary work holder H for effecting ro-

tation of the latter by rotation of shaft 57. In this instance we have provided a form of transmission of our invention which embodies the use of rotary drums and flat, flexible bands connected therebetween for transmitting the rotary movements of the drum 58 to the work holder H. Such transmission or drive includes a drum 60 mounted on shaft 57 at the outer side of drum 58. The rotary work holder H includes the horizontally disposed shaft or spindle 61 which mounts on its outer end a drum 62 which is in lateral alignment with drum 60 on the shaft 57. A thin, flat flexible steel or the like material band 63 is connected at one end to the drum 60 and extends over and across the upper side thereof and forwardly to and across the under side of the peripheral surface of the drum 62 on the spindle 61 of the work holder H, with the end of the band on drum 62 being secured to such drum. A second band 64 similar to band 63, is attached at one end to the under side of drum 60 at the outer side of band 63 and this band 64 is extended around the under side of the peripheral surface of drum 60 and upwardly to and over the upper side of the peripheral surface of drum 62 with the end of the band being connected to the drum 62. Thus, rotation of drum 60 in a clockwise direction, when facing the left-hand side of the machine, will wind band 64 onto the drum 60 and unwind this band from drum 62 to effect rotation of the latter drum in the opposite direction or counterclockwise. During such operation band 63 unwinds from drum 60 and winds onto drum 62. In the reverse operation when drum 60 is rotated counterclockwise, band 63 is wound onto drum 60 and unwound from drum 62, while the band 63 winds onto drum 60 and unwinds from drum 62, so that the latter drum is then rotated by the bands in a clockwise direction. The foregoing arrangement of drums 60 and 62 with the transmission bands 63 and 64 connected therebetween, eliminates slippage and backlash and insures accurate transmission to drum 62 and the rotary work holder H of the precise degree of rotary movement of the driving drum 60.

In the machine of this example, the drums 60 and 62 are mounted and journaled within a supporting and housing structure 65 which is mounted at its forward end on the left-hand end of work table W at the outer side of work holder H, and which extends rearwardly to and receives therethrough the shaft 57. The work holder spindle 61 extends into the forward end of structure 65 with the drum 62 on the spindle located in such forward end of the housing structure. The drum 60 is mounted and journaled in the rear end portion of structure 65 with the shaft 57 splined thereto for movement of drum 60 axially in either direction therealong while being maintained in rotary driven relation therewith. The drive or transmission supporting and housing structure 65 and the drums 60 and 62 mounted therein with the transmission bands 63 and 64 therebetween, are movable as a unit assembly cross-wise of the machine by cross-wise movements of table W upon and across saddle S with the drum 60 being moved axially along shaft 57. The shaft 57 is preferably provided of extended length outwardly to give an extended range of cross-wise movement of work table W to the left to thereby accommodate a wide range of work piece lengths while maintaining operative driving connection between drum 60 and the driving shaft 57.

11

By our invention we provide a movement ratio compensating, adjustable bar unit U for transmitting the movements of the pantograph actuated slide member 41 to the slide carriage 50, in such a manner as to move carriage 50 in a selected predetermined ratio, but in the opposite direction, to the movements of slide member 41. This ratio compensating unit U in the particular expression thereof adapted to the example machine, includes a bar or lever 70 which is pivoted at its upper end to the under side of the slide member 41 about a horizontal axis perpendicular to the path of straight line movements of slide member 41, that is, parallel with the straight line cross-wise movements of cutter head 12. Such pivotal mounting of the upper end of bar 70 to slide member 41 is effected by a pivot pin 71 secured in horizontal position across a depending yoke 72 provided at and depending from the under side of slide member 41, with the upper end of bar 70 being pivotally mounted on 71 between the arms of the yoke.

Bar 70 includes at its upper pivoted end, a head 70a of greater thickness than the remainder of the body length of the bar. A pivot block 73 is slidably mounted on bar 70 below head 70a for adjustments vertically in either direction lengthwise or axially of the bar. The pivot block 73 slidably receives therethrough the bar 70, and the portion 74 of the block at the outer side of bar 70 is formed with an internally threaded bore 74a parallel with the longitudinal axis of the bar and opening through the upper end edge of block portion 74. An externally threaded micrometer screw 75 has its lower end threaded into block bore 74a, and this screw extends upwardly along the outer side of the bar to a fixed bearing member 76 secured on the bar adjacent the inner end of head 78. The upper end of micrometer screw 75 is journaled in bearing member 76 and is held by that member against movements axially relative to the bar. The end of screw 75 above bearing member 76 is provided with a knurled finger gripping head 77 for ready manual rotation of the screw in either direction to effect adjustments of the pivot block 73 longitudinally of bar 70.

At the inner side of the ratio compensating bar unit U, the machine organization provides a fixed, vertically disposed structure 80 in the form of a wall, which mounts and supports on the outer side thereof, opposite and facing, pivot block 73 of unit U, a vertically disposed single rail 81. A pivot carriage 82 having spaced wheels or rollers 83 journaled thereon, is mounted in vertically disposed position with the rollers 83 in rolling engagement with the opposite side edges of rail 81, so that pivot carriage 82 is vertically movable on rail 81 and is constrained by such rail to a straight line path of movement perpendicular to the paths of movement of slide 41 and slide carriage 50. This pivot carriage 82 mounts a forwardly extended, horizontally disposed pivot member 84 which is pivotally coupled to and connects pivot block 73 with the pivot carriage 82. Pivot member 84 and pivot carriage 82 thus form a vertically adjustable, horizontal pivot for the block 73, about which the bar 70 may be swung or rocked by horizontal movements of the slide member 41 in either direction on and along slide rods 42. Body 52 of the carriage 50 is provided along its rear or inner side wall with a vertical rail or single track 85. A carriage 86 provided with spaced rollers 87 journaled thereon, is mounted on rail 85 with the spaced rollers 87 in

5 rolling engagement with the opposite vertical side edges, respectively, of the vertical rail 85. The carriage 86 is thus vertically movable upwardly or downwardly on rail 85 and is constrained by the rollers 87 engaged with the rail, to a straight line path of movement parallel with the vertical path of movement of pivot carriage 82, but perpendicular to the straight line paths of horizontal movements of slide member 41 and carriage 50. The lower end of the bar 70 below pivot member 84 is pivotally connected to the slide carriage 86 by a horizontal pivot member 88 having its axis parallel with the axes of pivot member 84 and with the pivot pin 71 which pivotally connects the upper end of bar 70 to the slide member 41.

The "throw" of the lower end of bar 70 of unit U may be adjusted by the micrometer screw 75 to raise or lower the pivot block 73 to thereby adjust the differential between the length of the lever arm between pivot member 84 and the pivot pin 71 which connects the upper end of the lever to slide member 41, and the length of the lever arm between pivot member 84 and the pivot 88 which connects the lower end of bar 70 to the carriage 86 and to the slide or band carriage 50. Adjustment of the pivot block 73 upwardly on the bar 70 increases the throw of the lower end of the bar, and hence the distance of movement of the band carriage 50 for a given distance of movement of the slide member 41, while adjustment downwardly of pivot member 84 decreases the throw and the distance of movement of band carriage 40 for a given movement of slide member 41. In this manner a fixed or predetermined ratio between the movements of the tracer T over a master or pattern P and the resulting degrees of rotational movement transmitted to a cylindrical work piece R may be maintained for engraving upon work pieces of different diameters, by proper adjustments of the unit U. In the example machine, the arrangement provides for reproducing the master design or pattern on the circumferential surface of the work piece to one-half (1/2) the size of the master design. Hence, to compensate for difference in work piece diameters in order to maintain accurately and with precision the 2:1 reduction, it is necessary to adjust the ratio bar unit U, so that a greater movement of the engraving cutter E over a work piece of smaller diameter is carried out by the pantograph movement converting and transmitting mechanisms, than for a work piece of greater diameter.

If desired, a suitable scale having division lines 89 may be provided along the outer side of bar 70 adjacent the forward longitudinal edge thereof for visual cooperation with a suitable adjacent index point on or adjacent structural edge of pivot block 73; with these scale lines suitably calibrated and provided with symbols indicating different work piece diameters. Thus, an operator may readily quickly effect an adjustment with accuracy and precision to accord with the requirements for a work piece of a given diameter.

Preferably, the weight of the pivot block 73, and of carriages 82 and 86, is counterbalanced, as by a weight 90 connected to one end of a cable 91 which extends over a suitable idler pulley and is connected at its other end to the pivot block, pivot member and pivot carriage assembly 73—82—84, as will be clear by reference to Fig. 4. Thus, ease of manual rotation of micrometer

screw 75 to raise and lower pivot block 73 and its associated structures, is insured.

Operational summary

In performing engraving operations on the circumferential surfaces of a roll or cylindrical work piece R with the example machine, the work piece is mounted in rotatable work holder H on the work table W between the work holder and the tail piece unit H' in position disposed longitudinally of the work table, that is, truly cross-wise relative to the machine and parallel with the straight line path of movements of cutter spindle 16. So mounted, the work piece R is rotatable about its longitudinal axis, which axis is horizontal and axially aligned with the axis of rotation of the work holder, and is parallel with the path of cross-wise movements of cutter head 12.

A desired pattern P is mounted and secured in proper position on the copy table D by the pattern holder F. This pattern P may be in the form of a flat brass, sheet iron, zinc or sheet plastic member, in which the master design has been cut or formed, either sunk or in relief. For the example machine which has a 2:1 reduction ratio, the master design formed on pattern P is of twice the size of the design to be reproduced therefrom on the circumferential surface of the work piece R.

The ratio compensating, adjustable bar unit U, is then adjusted to a setting in accordance with the diameter of the work piece R which is to be engraved. This adjustment and setting in the instant example, is effected by adjusting the pivot block 73 in the required direction along bar 70 until the index point on block 73 is lined up with that scale division line 89 for the particular diameter of the work piece R. By this adjustment cross-wise movements of the tool E on cutter spindle 16 and the movements of the surface of work piece R past tool E effected by rotation of the work holder H, are caused to be in accurate 2:1 reduction ratio to the corresponding movements of the tracer T over the pattern P. True cross-wise movements of the tracer T along straight line paths parallel with the axis of rotation of work piece R will be precisely reproduced as cross-wise movements of the tool E along the work piece R axially thereof and through a distance precisely one-half ($\frac{1}{2}$) the distance of the corresponding movement of tracer T. During such true cross-wise movements of tracer T, the floating pivot 43 which couples the pantograph G with the slide member 41, will not have translational movements imparted thereto, and, hence, will not effect any movements of the slide member 41 along its mounting slide rods 42. Therefore, during such true cross-wise tracer movements, there will be no rotation of work holder H and the work piece R mounted therein.

True in and out movements of tracer T over the pattern P, that is, movements in either direction along straight line paths perpendicular to the axis of rotation of work holder H and work piece R and to the straight line path of pure true cross-wise movements, will, through the pantograph G, floating pivot 43, slide member 41, ratio compensating bar U, band carriage 50 and the drums 60 and 62 with their movement transmitting bands

63 and 64, effect rotation of work piece R through a degree of rotational movement to thereby move the circumferential surface of the work piece past the cutter E a distance precisely one-half ($\frac{1}{2}$) of

the distance of movement in and out of the tracer T. During such true in and out movements of the tracer T, the cutter has neither in and out movements nor cross-wise movements but is maintained in fixed position by the slide member 20 and slide rods 17. Under such conditions the pantograph G is swingable laterally about the common axis of cutter head 12 and cutter spindle 16, as a fixed axis. In all such in and out movements of the tracer T, as well as in all cross-wise movements and compound movements partaking of both cross-wise and in and out movements, the axes of the tracer T, cutter spindle 16 and pivot 43 are maintained in a straight line lying in a common vertical plane passing therethrough.

In scanning or following the master design on a pattern P, the tracer T may be moved along paths, either rectilinear or curved, between the straight line paths of true in and out and of true cross-wise movements defining the two (2) major dimensions of the pattern and of the design to be reproduced therefrom. Such movements thus are compounded and include both a component of cross-wise movement and a component of in and out movement. Under such compound directional movements of tracer T over the pattern, the cutter spindle 16 and cutter E will be moved cross-wise and longitudinally along and relative to the work piece, and simultaneously the work holder H will be rotated to revolve the work piece R relative to cutter E in synchronization with the cross-wise movement of the cutter spindle, so that, such simultaneous movements of the cutter spindle and the work piece will be compounded into a resultant relative movement between the cutter E and the work piece R which will move the cutter over the circumferential surface of the work piece along a path precisely corresponding in direction and distance to and in precisely scaled reduction of, the path of the tracer.

The machine of the example embodiment has the capacity for handling work pieces up to approximately forty inches (40") in lengths and from approximately six to twelve inches (6" to 12") in diameters, and is designed to effect a reproduction on the circumferential surface of a work piece of the master design on a pattern P at a reduction ratio of 2:1. The machine further provides as the maximum area which can be covered by the engraving cutter E at one setting of the work piece, an area of approximately five inches by approximately twenty inches (5" x 20"). In the usual roll engraving operations which are carried out on a machine of this general character, an entire design may be required to be engraved on and completely around and from end to end of, the circumferential surface of the roll or work piece. In carrying out such an operation only a small segment or section of the entire design is required to be placed on a pattern P, so that, the complete surface of the roll may be engraved by repeating the pattern segment of the design around and along the roll. Repeating the engraving of the pattern segment 65 of the design in order to cover the entire roll surface, is accomplished by indexing the work piece or roll as each segment is completed around the roll and by indexing the work table W longitudinally, that is cross-wise on saddle S, as each segment is completed axially or lengthwise of the roll.

It will also be evident that various other embodiments, forms, designs, arrangements and combinations may be resorted to without departing from the broad spirit and scope of our

15

invention; and hence we do not wish to limit our invention in all respects to the specific example embodiment, or to the specific constructions and arrangements thereof, except as may be required by specific, intended limitations thereto appearing in any of the claims hereto appended.

What we claim is:

1. In an engraving machine, in combination; a supporting structure; a rotatable work holder mounted in fixed position on said supporting structure and being adapted to mount a roll-like work piece in position with its longitudinal axis disposed cross-wise of the machine for rotation of the work piece about such axis; a cutter spindle positioned with its axis perpendicular to the axis of work piece rotation; means mounting said cutter spindle and constraining it to movements in either direction along a straight line path parallel with the axis of work piece rotation; a pantograph linkage pivotally connected on and supported from said cutter spindle mounting means and being laterally swingable about and in a plane perpendicular to the axis of said spindle; a tracer connected with said pantograph linkage in position with its axis parallel with the axis of said cutter spindle and being adapted to be universally laterally moved over a pattern to swing said linkage laterally about the axis of said cutter spindle; mechanism for rotating said work holder; a pivotal connection between said work holder rotating mechanism and said pantograph linkage providing a pivot axis spaced along said linkage from and parallel with the axis of said cutter spindle; and said tracer, cutter spindle and pivotal connection between said linkage and said work holder rotating mechanism being relatively mounted to be maintained with the axes thereof in a straight line lying in a common plane passing therethrough in all positions of operation thereof by said tracer and pantograph linkage.

2. In an engraving machine, in combination; a supporting structure; a rotatable work holder mounted in fixed position on said supporting structure and being adapted to mount a roll-like work piece in position with its longitudinal axis disposed cross-wise of the machine for rotation of the work piece about such axis; a cutter spindle positioned with its axis perpendicular to the axis of work piece rotation; means mounting said cutter spindle and constraining it to movements in either direction along a straight line path parallel with the axis of work piece rotation; a pantograph linkage pivotally connected on and supported from said cutter spindle mounting means in position for lateral swinging about and in a plane perpendicular to the axis of said spindle; a tracer connected with said pantograph linkage and being mounted for universal lateral movements over a pattern to correspondingly laterally swing said linkage about the axis of said cutter spindle; mechanism for rotating said work holder; and a pivotal connection between said work holder rotating mechanism and said pantograph linkage providing a pivot axis spaced along said linkage from and parallel with the axis of said cutter spindle.

3. In an engraving machine, in combination; a supporting structure; a rotatable work holder mounted in fixed position on said structure and being adapted to mount therein a roll-like work piece in position with its longitudinal axis disposed cross-wise of the machine for rotation of the work piece about such axis; a cutter spindle positioned with its axis perpendicular to the axis

of work piece rotation; movable means mounting said cutter spindle and constraining it to movements in either direction along a straight line path parallel with the axis of work piece rotation; a pantograph linkage pivotally supported in position for lateral swinging in a plane perpendicular to the axis of said spindle; a tracer connected with said pantograph linkage for universal lateral movements over a pattern to correspondingly laterally swing said linkage; said pantograph linkage being adapted to move said cutter spindle along its straight line path in scaled relation to and solely by movements of said tracer along straight line paths parallel with the axis of work piece rotation; mechanism for rotating said work holder; adjustable ratio compensating means pivotally coupled with said pantograph linkage for actuation by said linkage, said ratio compensating means being also operatively connected with said work holder rotating mechanism for effecting operation of said rotating mechanism to rotate said work holder through degrees of rotation at a predetermined ratio to and solely by movements of said tracer along straight line paths perpendicular to the axis of work piece rotation, and said tracer, cutter spindle and pivotal coupling between said ratio compensating mechanism and said linkage being relatively mounted to be maintained with the axes thereof in a straight line passing therethrough in all positions of operation thereof.

4. In an engraving machine, in combination; a supporting structure, a rotatable work holder mounted in fixed position on said supporting structure and being adapted to mount a roll-like work piece in position therein for rotation thereby about its longitudinal axis; a cutter spindle positioned with its axis perpendicular to the axis of work piece rotation and being adapted to mount at its work piece end a cutter in cutting relation with the circumferential surface of the work piece; movable carriage means mounting said cutter spindle and being constrained to movements in either direction along a straight line path parallel with the axis of work piece rotation; a pantograph linkage pivotally connected on and supported from said cutter spindle carriage means in position for lateral swinging about and in a plane perpendicular to the axis of said cutter spindle; a tracer connected with said pantograph linkage and being mounted for universal lateral movements over a pattern to correspondingly laterally swing said linkage; said pantograph linkage being adapted to move said cutter spindle in either direction along its straight line path of movement at a fixed ratio relative to and solely by movements of said tracer along straight line paths parallel with the axis of work piece rotation; mechanism operatively connected between said rotary work holder and said pantograph linkage for causing rotation of said work holder by movements of said linkage effected solely by movements of said tracer along straight line paths perpendicular to the axis of work piece rotation; and said work holder rotating mechanism including, adjustable ratio compensating means for selectively setting said mechanism to effect degrees of rotation of said work holder at a predetermined ratio relative to movements of said tracer along straight line paths perpendicular to the axis of work piece rotation.

5. In an engraving machine for engraving on and around the circumferential surfaces of roll-like work pieces, in combination; a rotatable work holder; a cutter spindle positioned with its

axis perpendicular to the axis of rotation of said work holder; said cutter spindle being mounted and constrained for movements in either direction along a straight line path parallel with the axis of rotation of said work holder; a pantograph linkage mounted for lateral swinging about and in a plane perpendicular to the axis of said cutter spindle; a tracer connected with said pantograph linkage for universal lateral movements over a pattern to correspondingly laterally swing said linkage; a movable member mounted for and constrained to movements in either direction along a straight line path perpendicular to the axis of rotation of said work holder; a pivotal connection between said movable member and said pantograph linkage at a location on the latter spaced therealong from said cutter spindle; said tracer, cutter spindle and pivotal connection being mounted with their axes parallel and maintained in a straight line lying in a common plane passing through said axes; and mechanism operatively connected between said rotary work holder and said movable member for effecting rotation of said work holder by movements of said member along its straight line path.

6. In an engraving machine, in combination; a rotatable work holder; a cutter spindle positioned with its axis perpendicular to the axis of rotation of said work holder; means mounting said cutter spindle for movements in either direction along and constrained to a straight line path parallel with the axis of work holder rotation; a pantograph linkage pivotally connected to and supported on said spindle mounting means for swinging laterally about and in a plane perpendicular to the axis of said spindle; a tracer mounted on said linkage for universal lateral movements over a pattern to correspondingly laterally swing said linkage about its pivotal axis on said spindle mounting means; a movable member mounted for and constrained to movements in either direction along a straight line path perpendicular to the path of movements of said cutter spindle; said movable member being pivotally connected to said linkage; a carriage mounted for and constrained to movements in either direction along a straight line path parallel with the path of movements of said movable member; a bar unit including a bar member pivotally mounted intermediate its ends between said movable member and said carriage for swinging about an axis perpendicular to the paths of movement of said carriage and said member; said bar member being pivotally coupled at its opposite ends to said movable member and said carriage, respectively; and mechanism connected between said carriage and said rotary work holder for converting rectilinear movements of said carriage into rotary movements of said work holder.

7. In the combination as defined in claim 6, said bar unit including; a pivot block mounted on said bar member for movements in either direction longitudinally therealong to selected positions of adjustment; and a pivot member mounted on said pivot block and being movable therewith and constituting the intermediate pivotal mounting for bar unit.

8. In the combination as defined in claim 6, a drum mounted spaced from said carriage at the side thereof opposite said bar unit and being mounted for rotation in either direction about an axis perpendicular to the path of straight line movements of said carriage; and flexible band members connected to said carriage and being ex-

tended to and oppositely wound on said drum for converting rectilinear movements of said carriage into rotary movements of said drum.

9. In the combination as defined in claim 6, a rotary shaft mounted in position with its axis disposed perpendicular to the path of straight line movements of said carriage; a drum on and in driving connection with said shaft; means connecting said drum with said carriage for converting rectilinear movements of the latter to rotary movements of said drum and shaft; a second drum keyed on said shaft in rotary driven connection therewith; said work holder including a rotary spindle and a drum mounted thereon in driving connection therewith; and flexible bands connected between and at their opposite ends being oppositely wound on said shaft mounted second drum and said work holder spindle mounted drum for transmitting rotation in either direction of said second drum to said work holder spindle mounted drum.

10. In an engraving machine, in combination; a rotatable work holder; a cutter spindle positioned with its axis perpendicular to the axis of rotation of said work holder; means mounting said cutter spindle for movements in either direction along and constrained to a straight line path parallel with the axis of work holder rotation; a pantograph linkage pivotally supported on said spindle mounting means for swinging laterally about and in a plane perpendicular to the axis of said spindle; a tracer connected with said linkage and being universally laterally movable over a pattern to correspondingly swing said linkage; a movable member mounted for and constrained to movements in either direction along a straight line path perpendicular to the axis of rotation of said work holder; a pivotal connection between and coupling said linkage to said movable member; a carriage mounted for and being constrained to movements in either direction along a straight line path parallel with the path of movements of said movable member; a ratio compensating bar unit pivotally mounted intermediate its ends and being pivotally coupled at its opposite ends to said movable member and said carriage, respectively; said bar unit including, a bar member, a pivot block mounted thereon for movements in either direction longitudinally therealong to selected positions of adjustment, a pivot member mounted on said pivot block and being movable therewith and constituting the intermediate pivotal mounting for said bar unit, and a micrometer screw journaled on said bar member and being threadedly engaged with said pivot block; and mechanism connected between said carriage and said rotary work holder for converting rectilinear movements of said carriage into rotary movements of said work holder.

11. In the combination as defined in claim 10, a scale provided on said bar member along the path of movements of said pivot block.

12. In an engraving machine, in combination; a rotatable work holder; a cutter spindle; means mounting said cutter spindle in position with its axis perpendicular to the axis of rotation of said work holder; a pantograph linkage pivotally supported on said spindle mounting means for swinging laterally in a plane perpendicular to the axis of said spindle; a tracer connected with said linkage and being universally laterally movable to correspondingly swing said linkage about its pivotal support on said spindle mounting means as an axis; a mechanism operatively connecting

said rotary work holder with said pantograph linkage at a pivotal connection with said linkage spaced from the point of pivotal support of said linkage on said spindle mounting means for effecting rotation of said work holder in scaled relation to movements of said tracer in either direction along straight lined paths perpendicular to the axis of rotation of said work holder, and said pivotal connection between said mechanism and said linkage, said cutter spindle, and said tracer being relatively mounted with their axes in a straight line passing therethrough in all positions of operation thereof.

13. In an engraving machine, in combination; a rotatable work holder; a cutter spindle; means mounting said cutter spindle in position with its axis perpendicular to the axis of rotation of said work holder; said cutter spindle mounting means constraining said spindle against movements in directions perpendicular to the axis of rotation of said work holder; a pantograph linkage of the parallelogram, jointed link type pivotally supported on said spindle mounting means for swinging laterally about the axis of said spindle as a pivot axis and in a plane perpendicular thereto; a tracer mounted on said linkage in position with its axis parallel with the axis of said spindle and being universally laterally movable to correspondingly swing said linkage about the axis of said spindle; a movable member mounted for movements along and constrained to a straight line path perpendicular to the axis of said spindle and to the axis of rotation of said work holder; a pivotal connection between said movable member and a link of said linkage spaced from the point of pivotal support of said linkage on said spindle mounting means; and mechanism operatively connected between said movable member and said rotary work holder for converting rectilinear movements of said member into rotary movements of said work holder.

14. In an engraving machine for engraving designs on and around the circumferential surfaces of roll-like work pieces, in combination; a rotatable work holder; a cutter head mounted for and constrained to movements in either direction along a straight line path parallel with the axis of work holder rotation; a cutter spindle journaled in said cutter head in position with its axis perpendicular to the axis of work holder rotation; a jointed link pantograph linkage pivotally connected to said cutter head for swinging bodily laterally about and in a plane perpendicular to the axis of said cutter spindle; a tracer mounted on said linkage for universal lateral movements over a pattern to correspondingly laterally swing said linkage; a movable member mounted for and being constrained to movements in either direction along a straight line path perpendicular to the axis of rotation of said work holder; a pivotal connection coupling said movable member to said linkage at a location on the linkage spaced from the point of pivotal connection of said linkage to said cutter head; and mechanism operatively connecting said rotary work holder with said member for converting rectilinear movements of said member into rotary movements of said work holder.

15. In an engraving machine for engraving designs on the circumferential surfaces of roll-like work pieces, in combination; a rotatable work holder; a cutter spindle positioned with its axis perpendicular to the axis of rotation of said work holder; movable means mounting and constraining said cutter spindle to movements in

either direction along a straight line path parallel with the axis of work holder rotation; a pantograph linkage pivotally coupled with said spindle mounting means for lateral swinging in a plane perpendicular to the axis of said spindle; a tracer connected with said pantograph linkage and being mounted for universal lateral movements over a pattern to correspondingly laterally swing said linkage; a first movable member mounted for and constrained to movements in either direction along a straight line path perpendicular to the axis of rotation of said work holder; said first movable member being pivotally coupled to said pantograph linkage; a second movable member mounted for and constrained to movements in either direction along a straight line path parallel with the path of movements of said first movable member; a ratio compensating unit pivotally mounted intermediate its ends and being pivotally coupled at its opposite ends to said first and second movable members, respectively; said unit including a bar member, a pivot block mounted thereon for movements in either direction longitudinally thereof along positions of adjustment thereon, a pivot member mounted on said pivot block and constituting the intermediate pivotal mounting for said unit, and means for adjusting said pivot block; and mechanism connected between said second movable member and said rotary work holder for converting rectilinear movements of said second movable member into rotary movements of said work holder.

16. In an engraving machine, in combination; a fixed supporting frame structure; a rotatable work holder mounted in fixed position on said fixed frame structure and being adapted to mount a roll-like work piece in position with its longitudinal axis disposed cross-wise of the machine for rotation of the work piece about such axis; a rotary cutter spindle positioned with its axis perpendicular to the axis of rotation of the work piece mounted in said work holder; movable means mounting and adapted to constrain said cutter spindle solely to movements in either direction along a straight line path parallel with the axis of rotation of the work piece; a tracer mounted for universal lateral movements over a pattern; a jointed-link parallelogram linkage unit operatively connected to said tracer and to said cutter spindle in position extending therebetween for transmitting movements of said tracer along straight line paths parallel with the axis of work piece rotation to said cutter spindle to thereby move said spindle along its straight line path; and mechanism for converting rectilinear movements to rotary movement coupled to said pantograph linkage and to said rotary work holder for operatively connecting said linkage unit and work holder for effecting rotation of the latter solely by in and out movements of said tracer along straight line paths perpendicular to the straight line path of movements of said cutter spindle and its mounting means.

17. In an engraving machine for engraving designs on the circumferential surface of roll-like work pieces, in combination; a rotatable work holder; a cutter spindle positioned with its axis perpendicular to the axis of rotation of said work holder; movable mounting means; said cutter spindle being mounted on said movable mounting means; constraining means adapted to confine movements of said movable mounting means and said cutter spindle mounted thereon solely to movements in either direction along a straight

line path parallel with the axis of work holder rotation; a pantograph linkage unit pivotally mounted and supported on said movable cutter spindle mounting means in position for lateral swinging as a unit about and in a plane perpendicular to the axis of said cutter spindle; a tracer connected with said pantograph linkage unit and being mounted for universal lateral movements over a pattern to correspondingly laterally swing said linkage unit; a movable member; means adapted to constrain movements of said movable member to movements solely in either direction along a straight line path perpendicular to the axis of rotation of said work holder; a pivotal connection between said movable member and said pantograph linkage unit; an adjustable-length link unit pivotally coupled to said movable member; and mechanism operatively coupled to said link unit and being adapted to be actuated thereby by movements of said movable member in either direction along its straight line path of movement to cause rotation of said work holder.

18. In an engraving machine for engraving on and around the circumferential surfaces of roll-like work pieces, in combination; a rotatable work holder; a cutter spindle mounted in position with its axis perpendicular to the axis of rotation of said work holder; means movably mounting and adapted to constrain said cutter spindle solely to movements in either direction along a straight line path parallel with the axis of work holder rotation; a pantograph linkage unit pivotally supported for lateral swinging about and in a plane perpendicular to the axis of

said cutter spindle; a tracer connected with said pantograph linkage for universal lateral movements over a pattern; a movable member; means adapted to constrain said movable member to movements solely along a straight line path perpendicular to the axis of rotation of said work holder; a pivotal connection between and coupling said movable member with said pantograph linkage unit; said pivotal connection, said tractor and said cutter spindle being mounted with their axes maintained in a straight line lying in a common plane passing through said axes in all positions of operation thereof; mechanism for rotating said work holder; and means operatively connecting said work holder rotating means with said movable member for converting rectilinear movements of the latter member into rotary movements of said work holder.

FREDDY STEINBRECKER.
